FIG. 1.

FIG. 2.

FIG. 3.

CHAS. R. WILLIAMS, INVENTOR
BY *Victor J. Evans* ATTORNEY

UNITED STATES PATENT OFFICE.

CHARLES R. WILLIAMS, OF COURTNEY, PENNSYLVANIA.

PAPER-HANGING MACHINE.

1,413,443.

Specification of Letters Patent. Patented Apr. 18, 1922.

Application filed June 13, 1921. Serial No. 477,233.

To all whom it may concern:

Be it known that I, CHARLES R. WILLIAMS, a citizen of the United States, residing at Courtney, in the county of Washington and 5 State of Pennsylvania, have invented new and useful Improvements in Paper-Hanging Machines, of which the following is a specification.

This invention relates to a paper hanging 10 machine, and more particularly to a machine for hanging wall paper.

One of the main objects of the invention is to provide a machine of the character stated of simple construction and operation 15 by means of which paper may be quickly and easily applied to walls and similar surfaces in strips. A further object is to provide a machine of the character stated by means of which the paste is applied to the 20 paper by the act of drawing the machine along the strip of paper, the paper being simultaneously applied to the wall surface. Further objects will appear from the detailed description.

25 In the drawings:

Figure 1 is a side view of a machine constructed in accordance with my invention as used.

30 Figure 2 is a central vertical longitudinal sectional view.

Figure 3 is an end view.

The machine comprises a boxlike casing 1 which is divided by a partition 2 into a paste receiving compartment 3 and a brush 35 compartment 4. A brush 5 is rotatably mounted in compartment 4, this brush being secured upon a shaft 6 rotatably mounted through the side walls of the casing and provided at one end with a crank-handle 7.

40 The partition 2 is provided with an opening 8 to permit paste which is placed in the compartment 3 to flow into the brush compartment 4. This paste collects in the lower rounded end portion 1^a of the casing

45 so that the lower portion of the brush is immersed in the paste. The upper end of casing 1 is provided with a suitable opening, normally closed by a plug 9, to permit the paste to be poured into compartment 3.

50 A suitable handle 10 is secured to the lower end of the casing to facilitate manipulation of the same.

The top of the casing is closed by a sheet metal guide and paper receiving member 11

of rectangular cross-section. This member 55 is provided at each end with a downwardly projecting flange 12 having bayonet slots 13 which engage about headed pins 14 secured to the end wall of the casing. This provides simple and efficient means whereby guide 60 member 11 may be readily secured to, or detached from, the casing, this guide member also providing a closure for the casing. At its upper end the guide member 11 is provided with lateral forwardly projecting 65 arms 15 which rotatably support a roller 16 for rolling out or smoothing the paper as it is applied to the wall surface. Through its inner wall guide 11 is provided with an opening 17 through which the upper portion 70 of the bristles of brush 5 project for contact with a strip 18 of paper drawn through the guide member 11.

In practice, after the strip of paper to be applied has been cut the proper length, the 75 end portion of this strip is inserted into member 11 so as to project a slight distance beyond roller 16. During insertion of the strip brush 5 is rotated by movement of the paper strip so as to cause paste to be applied 80 to the underface of the paper. After this has been done, the upper end of the strip of paper is applied to the surface of the wall so as to adhere thereto, and the machine is then moved downwardly with the roller 16 85 bearing against the outer face of the paper. This causes the paper to pass through guide member 11, and during such passage of the paper the brush applies paste to the underface of the paper. The crank-handle 7 is 90 used in initially inserting the paper through member 11, the brush being manually rotated after the paper has been inserted an appreciable distance across the opening 17 thus feeding the paper through member 11 95 and simultaneously applying paste to the paper.

What I claim is:—

1. In a device of the character described, a casing, a brush rotatably mounted in said 100 casing, a tubular paper receiving member secured upon the top of the casing and provided through its inner wall with an opening, said brush projecting through said opening, and a smoothing roller rotatably 105 supported at the upper end of said member.

2. In a device of the character described, a casing divided into an upper paste receiv-

ing compartment and a lower brush compartment communicating with said upper compartment, a brush rotatably mounted in the brush compartment, a tubular paper receiving member secured upon the top of the casing and provided through its inner wall with an opening, said brush extending

through said opening, and means at the upper end of said member for applying pressure to the paper as it is applied to the 10 surface of a wall.

In testimony whereof I affix my signature.

CHARLES R. WILLIAMS.
